F. MANKEY.

PANEL.

No. 16,408.

Patented Dec. 8, 1885.

UNITED STATES PATENT OFFICE.

FREDERICK MANKEY, OF WILLIAMSPORT, PENNSYLVANIA.

DESIGN FOR A PANEL.

SPECIFICATION forming part of Design No. 16,408, dated December 8, 1885.

Application filed July 18, 1885. Serial No. 172,005. Term of patent 7 years.

To all whom it may concern:

Be it known that I, FREDERICK MANKEY, of Williamsport, Lycoming county, Pennsylvania, have invented and produced a new and original Design for Panels, of which the following is a specification, reference being had to the accompanying photograph, forming part hereof.

My design is intended for an ornamental panel such as is used in doors, wainscots, &c.; and it consists in the central frusto-pyramidal elevation, A, which is diamond-shaped, with its longest diameter placed longitudinally the panel, as shown. At each angle of the central diamond is a smaller pyramidal diamond, B. Between the diamonds B are pyramidal rhomboidal elevations C. The elevations A, B, and C are separated by channels or spaces D E F G. The entire figure is diamond shaped, as shown.

I claim—

1. The design for a panel, substantially as herein shown and described, which consists of the diamond-shaped frusto-pyramidal elevation A, the diamond-shaped pyramids B, the pyramidal elevations C, and intermediate channels or spaces, D E F G. 25

2. The design for a panel, substantially as herein shown and described, which consists of the diamond-shaped frusto-pyramidal elevation A, the diamond-shaped pyramids B, the pyramidal elevations C, and intermediate channels or spaces, D E F G, a different grain-marking appearing on the inclined sides of said elevations from that which appears in 35 said channels. 30

FREDERICK MANKEY.
